(57) **CLAIM**

The ornamental design for a component mixing chamber, as shown and described.

DESCRIPTION

FIG. 1 is a first isometric view of a component mixing chamber;

FIG. 2 is a second isometric view of the component mixing chamber;

FIG. 3 is a third isometric view of the component mixing chamber;

FIG. 4 is a left side view of the component mixing chamber;

FIG. 5 is a top plan view of the component mixing chamber;

FIG. 6 is a right side view of the component mixing chamber;

FIG. 7 is a bottom plan view of the component mixing chamber;

FIG. 8 is a front elevation view of the component mixing chamber; and,

FIG. 9 is a rear elevational view of the component mixing chamber.

The broken lines shown represent portions of a component mixing chamber and form no part of the claimed design.

1 Claim, 5 Drawing Sheets
